UNITED STATES PATENT OFFICE.

JOHN T. RIDDELL, OF EVANSTON, ILLINOIS.

ATHLETIC-SHOE CONSTRUCTION.

Application filed December 29, 1926. Serial No. 157,667.

This invention relates to improvements in athletic shoe construction, of the type utilizing relatively large cleats, such as commonly employed by football players.

5 An object in view is the effective retention of the sole of an athletic shoe against breaking or other distortion and the retention of the cleats in proper relation and operative condition, especially where relatively widely 10 spaced cleats are utilized.

With this and further objects in view, as will in part hereinafter become apparent and part be stated, the invention comprises certain novel construction, combinations and 15 arrangements of parts as hereinafter specified and claimed.

In the accompanying drawing,

Fig. 1 is a longitudinal, vertical section through a fragment of a shoe embodying the 20 features of the present invention, the section being taken on the planes indicated by line 1-1 of Fig. 2.

Fig. 2 is an inverted plan view of the shoe as seen in Fig. 1.

25 Fig. 3 is a similar plan view of the bridging plate for the sole detached and shown on an enlarged scale.

Fig. 4 is a similar view of the heel bridging plate on a reduced scale relative to Fig. 30 3, and on an enlarged scale relative to Figs. 1 and 2.

Fig. 5 is an enlarged, fragmentary, vertical, longitudinal, axial section through the sole and one of the cleats, parts being seen in 35 elevation.

It has heretofore been proposed to stabilize the soles of shoes, both of the athletic type and of the ordinary type, by the interposition of a metal plate within the construction of the sole of the shoe. It has also been proposed to employ in the sole of an ordinary, non-athletic shoe a plate of spring metal anchored in the heel portion of the sole, and extending across the instep and 40 tread portion of the sole to afford a sort of cantilever action for rendering added resiliency to the action of walking. However, all of these proposed constructions fail to afford the requisite protection for cleats on athletic shoes of the type to which the present invention is particularly applicable. The effort in said proposed constructions is to distribute the reactive stresses from the 45 cleats to enhance the stability of the sole structure, and, in the case of the spring plate, to afford a resilient support for the

instep. I am unaware of any proposed use heretofore of a spring plate to which cleats are anchored, or soles to which cleats are anchored, which soles are provided with 60 spring plates.

In athletic shoes of the type requiring cleats, and especially the larger forms of cleats, it is found that, for some purposes, widely spaced cleats are desirable, and such arrangement has come to be known as the self-clearing cleats. Cleats too closely assembled soon have the intervening spaces filled with mud or other foreign substances and the cleats proportionately lose their 65 efficacy. To obtain the best type of self-clearing arrangement of cleats, therefore, it is desirable to have the cleats spaced apart as far as may be reasonably possible within the limits of the area of the shoe sole being considered. The result is that a very substantial section of shoe sole exists between any two cleats, and in practice, where such self-clearing cleats are employed, the average or 70 ordinary shoe sole of entire leather construction buckles, bends or breaks between cleats, or otherwise gives and allows the cleats to assume relatively distorted positions, especially after such soles become saturated with moisture, which largely depreciates and 75 sometimes wholly destroys the utility of the cleats. A plate of soft iron or soft steel, even when effectively anchored directly to the cleats, is liable to be permanently bent out of proper position, and a rigid metal 80 plate similarly anchored is liable to break under the stress of two cleats moving relative to each other, so that such plates will not serve to effectively avoid the danger to 85 or deterioration of the sole as above suggested. It is the object of the present invention to prevent such injury or deterioration of a sole provided with self-clearing 90 cleats by utilizing a spring steel or other appropriate spring metal plate for bridging 95 between cleats in a manner to effectively limit deflecting of the cleats under stress, and to restore the cleats to normal position immediately upon being released from such 100 deflecting stresses.

Referring to the drawing by numerals, 1 indicates an athletic shoe having the sole 2 and the heel 11. Sole 2 may, so far as the present invention is concerned, be of any ordinary or well known structure, so far as 110 the leather constituents are concerned. However, forming an essential part of the sole 2,

is a spring plate 3, preferably of thin sheet steel, interposed between the inner and the outer laminations of the sole 2. The plate 3 is located in the tread portion of the sole and 5 is shaped to conform to such portion. A similar plate 4, corresponding in contour to that of the heel 11 and arranged above the heel, is also incorporated as an integral part of the sole structure. For purposes of the 10 appended claim, the heel is considered a part of the sole. The plates 3 and 4 are retained firmly and effectively in place by the stitching or other connecting means employed for securing the laminations of the sole 2 together, so that neither plate 3 nor plate 4 is 15 capable of any edgewise or other movement independent of the other constituents of the sole. Plate 4, of course, is formed, as seen in Fig. 4, of a contour conforming to and 20 slightly less in area than that of the heel 11.

Fixed to and extending down from the tread portion of sole 2 and from the heel 11 are cleats 5, 5, spaced for producing a self-clearing construction, which is especially 25 desirable in shoes of this character. Each cleat 5 is anchored exactly the same as all the other cleats, except that the heel cleats have slightly longer anchoring bolts or studs, as will be well understood, and, therefore, a 30 detailed description of the anchorage of one cleat is applicable to all.

For each cleat 5, a bolt or stud 6 extends through the sole, or heel, and outstands therefrom. A washer 7, preferably of metal, 35 surrounds the outer portion of bolt 6 and is clamped firmly against the underface of the sole by a nut 8. A nut 9 is preferably imbedded in each cleat 5 and the cleat is screwed home on the extended shank of the bolt 6 to a position with the nut 9 threaded 40 along the shank of bolt 6 sufficiently for insuring a firm and effective seating of cleat 5 against washer 7. Each bolt 6, in extending through the sole or heel, extends through 45 aperture 10 formed in the respective plate 3 or 4 for accommodating the bolt. Each aperture 10 is preferably proportioned to snugly accommodate the passage of the bolt, and in assembling the parts after the plates 50 3 and 4 are in position, it is necessary to utilize appropriate means or methods for

aperturing the sole 2 in alignment with the apertures 10. Templets may be employed for this purpose. Thus, the bolts 6 effectively engage the plates 3 and 4 and are 55 not at liberty, therefore, to move laterally relative to the plates, or to have any other displacement movement without a proportional dislocation of engaged parts of the plate. Each of plates 3 and 4 is of spring 60 metal, preferably the finest obtainable clock spring being used.

The spring metal plate engaged by two spaced bolts 6, therefore, not only resist reactive stresses and uniformly distributes 65 them, but also bridges the space between cleats in the sense of guarding the sole against permanent buckling, stretching, giving or other displacement whereby dislocation of the cleats may occur. The cleats are, 70 therefore, effectively and rigidly held in place, and, if temporarily moved, are restored to normal relative position by the spring plate as soon as released from the temporary distorting stress. 75

There is no effort made in the use of the plates 3 and 4 to effect a cantilever action or any other resiliency of the shoe sole as a whole. In fact, the entire instep area of the sole is left without a plate of any kind, so as 80 to leave a hinge between the heel and the tread areas of the sole.

What is claimed is:

In athletic shoe construction, in combination a shoe sole; a flexible metallic spring 85 plate assembled within said sole; relatively widely spaced self-cleaning cleats outstanding from said sole; anchoring studs extending through said plate and adapted to yield vertically with respect thereto; said cleats 90 secured to said studs; the upper end of said studs imbedded within said sole, above said plate, for anchoring said cleats to said sole and to said plate; said plate bridging the space between said cleats and adapted to 95 yield for permitting sideways flexing of said cleats and to prevent permanent distortion thereof.

In testimony whereof I have signed my name to this specification.

JOHN T. RIDDELL.
